UNITED STATES PATENT OFFICE

148,381

DESIGN FOR A PORTABLE INTERNAL- COMBUSTION ENGINE

Willard J. Oehrlein, Leo J. Lechtenberg, and Clifford Brooks Stevens, Milwaukee, Wis., assignors to Briggs & Stratton Corporation, Milwaukee, Wis., a corporation of Delaware

Application February 7, 1947, Serial No. 136,770

Term of patent 14 years

(Cl. D77—1)

To all whom it may concern:

Be it known that we, Willard J. Oehrlein, Leo J. Lechtenberg, and Clifford Brooks Stevens, all citizens of the United States, residing at Milwaukee, in the county of Milwaukee and State of Wisconsin, have invented a new, original, and ornamental Design for Portable Internal Combustion Engine, of which the following is a specification, reference being had to the accompanying drawings, forming part thereof.

This is a continuation-in-part of applicants' prior application Serial No. D. 133,056, filed September 4, 1946, now abandoned.

The dominant features of our design are those illustrated in full lines.

We claim:

The ornamental design for a portable internal combustion engine, as shown and described.

WILLARD J. OEHRLIN,
LEO J. LECHTENBERG,
CLIFFORD BROOKS STEVENS.
